UNITED STATES PATENT OFFICE.

JOHN C. McLACHLAN, OF TORONTO, ONTARIO, CANADA.

METHOD OF PRODUCING CAST SHELL-PROJECTILES.

1,286,375.

Specification of Letters Patent.

Patented Dec. 3, 1918.

Application filed July 31, 1916. Serial No. 112,332.

To all whom it may concern:
Be it known that I, JOHN CAMPBELL McLACHLAN, a subject of the King of Great Britain, and resident of the city of Toronto, 5 county of York, Province of Ontario, in the Dominion of Canada, have invented certain new and useful Improvements in Methods of Producing Cast Shell-Projectiles, as described in the following specification and 10 illustrated in the accompanying drawings, that form part of the same.

This invention relates to a method and apparatus for producing projectiles or shells, and is an improvement upon the invention 15 disclosed in my prior specification 56,365, filed October 18th 1915.

In projectiles produced with the apparatus of said prior application, it was found that the edges of the annular groove formed 20 in the projectile and adapted to receive the driving band could not be formed sharp and even owing to the quick cooling of the metal. It is the principal object of this invention to provide a method and means 25 whereby the said edges may be made sharp and even, to fit snugly to the driving band.

The principal feature of this invention consists in the method of forming the annular groove for the driving band by molding 30 the metal forming the marginal edges of the groove to project beyond the main surface of the body of the projectile and subsequently removing the projecting portion.

This and other features of the invention 35 will be described in connection with the drawings and pointed out in the appended claims.

Referring now to the accompanying drawings:

40 Figure 1 is a half elevation and longitudinal sectional view of the mold used in casting the projectile or shell.

Fig. 2 is a half elevation and sectional view of the upper end of a projectile or shell 45 cast in the mold illustrated by Fig. 1 and showing the ridges at the marginal edges of the annular groove which receives the driving band.

Fig. 3 is a cross sectional view taken on the 50 line 3—3 of Fig. 1.

Like numerals of reference indicate corresponding parts in each figure.

Referring to the drawings, it will be seen that the mold comprises a circular base 1 55 having an axially extending core 2 formed on the upper side thereof and with a cen-

trally extending bore 3. The mold further comprises a cylindrical member 4 which is provided at its lower end with a flange 5 which is adapted to be secured to the circular 60 base 1 and with a seat 6 adapted to receive the core 2, and at its upper end with a flange 5^a having a beveled boss 5^b.

The mold still further comprises a pair of substantially semi-cylindrical members 4^a 65 which are provided at their lower ends with a flange 4^b having a circular beveled recess 4^c which is adapted to be secured to the flange 4^d and with the beveled seat 4^e adapted to receive the beveled boss 5^b. 70

The chill members are provided with radially extending fins or flanges 7 to aid in the rapid dissipation of the heat of the casting. At their upper ends the members 4^a are formed with a circular seat 8 which is 75 adapted to receive the head block 9. This head block is held in position by means of a fastening ring 10 which is suitably connected to the members 4^a. The head block is provided with openings 11 and 12, one of 80 which forms the pouring entrance and the other the gas vent.

A sleeve 19 is fitted in the bore 3, and a tubular perforated core center extends 85 through the sleeve 19 and is rigidly supported in central alinement within the mold. This tubular member extends substantially through the entire length of the mold and at its upper end 16 is perforated, the lower end being open. 90

As clearly shown in Fig. 3, the tubular core is adapted to have placed thereon a dry sand core 18 having longitudinally extending slots 18^a which form in the casting longitudinally extending ribs 18^b. This dry sand core is 95 shaped externally to the exact inner outline of the projectile or shell to be cast.

As clearly shown in Fig. 1 adjacent the upper end of the interior of the semi-cylindrical members 4^a an annular recess 25 is 100 formed. This recess has flaring sides 13 which are beveled off to meet the inner cylindrical surface of the members 4^a, thus forming the bevels 13^b. This groove is vented by means of the holes 13^a. 105

A dry sand core 14 is adapted to be seated in the recess 25 and snugly fits the bottom and the two sides 13 of said recess, but does not contact with the beveled surfaces 13^b. Thus two annular grooves 26 are formed between the said core and the bevels 13^b. Because of these grooves 26, ridges 14^b will be 110

cast on the projectile at the marginal edges of the annular groove 14^a. These circumferentially extending ridges are removed in any suitable manner such as by grinding or 5 machining, so that their outer surface is flush with the outer cylindrical surface of the projectile. The dotted lines in Fig. 2 illustrate the form of the projectile after the ridges 14^b have been removed.

10 It is obvious that by the above described method and means that even, sharp and accurate marginal edges are formed for the groove 14^a. This is a very important feature because the driving band is placed in the 15 groove under pressure and must fit the edges of the groove perfectly.

The provision of the sand core 2 at the nose end of the shell is an important feature as the metal of the end face is not 20 chilled and is therefore easily machined to fit the fuse cap.

What I claim as my invention is:—

1. A method of producing a cast projectile with an annular groove adapted to hold 25 a copper gas band consisting in pouring a metal into a mold to cast the projectile forming an annular groove in the periphery and annular ridges projecting beyond the main peripheral surface of the projectile, and 30 finally cutting down said projecting ridges

to form a surface of uniform diameter to the edges of the groove and forming sharp acute angled edges to the groove.

2. A method of producing cast projectiles consisting in first forming a chill mold with 35 an annular groove in its inner wall, said groove having outwardly beveled edges, then placing in said groove a dry sand core having beveled edges spaced from the beveled edges of the groove, then pouring a molten 40 metal into the mold to form the shell, the metal flowing into the spaces formed between the core and the mold and forming a groove in the shell, and ridges on the outer wall at the marginal edges of the groove, 45 and finally removing the projecting ridges so as to form sharp acute angled edges to said groove.

3. A method of producing a cast projectile, consisting in providing a chill mold and a core, and a supplementary sand core arranged at the bottom to form the end of the mold forming the nose end of the shell, then pouring the metal into the mold to 50 form the shell, the surface at the nose end being formed of softer texture than the remaining portion of the shell through contact with the sand surface of the mold.

J. C. McLACHLAN.
